(57) **CLAIM**

The ornamental design for a beverage container holder, as shown and described.

DESCRIPTION

FIG. 1 is a top, front perspective view of a beverage container holder;

FIG. 2 is a front view thereof, the rear view being a mirror image of the front view;

FIG. 3 is right side view thereof, the left side view being a mirror image of the right side view;

FIG. 4 is a top view thereof; and,

FIG. 5 is a bottom view thereof.

All broken lines represent unclaimed features of the article to which the design is applied.
